[57] CLAIM

The ornamental design for a sorter for copying machine, as shown and described.

DESCRIPTION

FIG. 1 is a front elevational view of a sorter for copying machine showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 333,834
DATED : March 9, 1993
INVENTOR(S) : Masataka Isomoto et al.

Page 1 of 1

It is certified that error appears in the above-identified patent and that said Letters Patent is hereby corrected as shown below:

Item [73] Assignee:

"Canan Kabushiki Kaisha," should read -- Canon Kabushiki Kaisha, --.

Signed and Sealed this

Fourth Day of September, 2001

Attest:

Nicholas P. Godici
